corporation of New York

Application August 30, 1944, Serial No. 115,124

Term of patent 14 years

(Cl. D87—3)

To all whom it may concern:

Be it known that I, Leon Halber, an individual without citizenship, residing in the city of New York, county of New York, State of New York, have invented a new, original, and ornamental Design for a Combined Billfold, Change Purse and Key Holder, of which the following is a specification, reference being had to the accompanying drawing, forming a part thereof, in which:

Fig. 1 is a perspective view of my new design for a combined billfold, change purse, and key

holder, the several parts being shown in open position.

Fig. 2 is a top plan view thereof with the billfold in the unfolded position; and

Fig. 3 is a perspective view thereof in closed position on a slightly reduced scale.

I claim:

The ornamental design for a combined billfold, change purse, and key holder, substantially as shown.

LEON HALBER.
